UNITED STATES PATENT OFFICE.

MICHAL KOLTUNSKI, OF CHICAGO, ILLINOIS.

FOLDING-BED TABLE.

Application filed August 12, 1921, Serial No. 491,763. Renewed May 11, 1922. Serial No. 560,249.

To all whom it may concern:

Be it known that I, MICHAL KOLTUNSKI, a citizen of Poland, residing at Chicago, in the county of Cook and State of Illinois, have invented certain new and useful Improvements in Folding-Bed Tables, of which the following is a specification.

This invention relates to certain new and useful improvements in folding bed tables and has particular reference to a table attachment for beds wherein the table is capable of various adjustments to assume different positions overlying the bed when in use and to be folded beneath the bed for storage when out of use.

With the above general object in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a rear elevational view of a folding bed table constructed in accordance with the present invention, the table top being partially broken away and clamped to the side rail of a bed illustrated in section, and further shown in a folding position beneath the bed by dotted lines, and

Fig. 2 is a side elevational view of the same.

Referring more in detail to the accompanying drawing, there is illustrated a folding bed table embodying a base support including right angularly disposed arms 1 and 2 that are supported on the angle iron side rail 3 of a bed. The clamping device for the base support embodies a U-shaped strap formed of spaced legs 4 and 5, the leg 5 engaging the inner face of the adjacent section of the rail 3 while the leg 4 engages the outer face of the leg 1, the bight of the clamp having an opening therein to permit sliding movement of the leg 1 as clearly illustrated. To hold the clamp in adjusted position, the upper end of the leg 4 is bifurcated to provide a pair of lugs 6 between which a lever 7 having a cam face 7' is pivotally mounted upon pin 8. A cross pin 9 carried by the lower end of the leg 1 will prevent the

clamp from becoming disengaged from the leg 1 of the base support when the same is dropped to its dotted line position shown in Fig. 1.

The supporting arms for the table top embody a lower curved section 10 having a tongue 11 at its lower end that is pivotally supported on the pin 12 carried by the spaced ears 13 formed on the base support, the angular adjustment of the supporting arm 10 being controlled by the thumb screw 14 in an obvious manner. A straight upper arm section 15 formed with spaced ears 16 and 17 at opposite ends respectively has the ears 17 enclosing the tongue 18 to form the upper end of the curved section 10 and pivotally supported on the pin 19, a thumb screw 20 holding the adjacent ends of the arms in adjusted positions.

A relatively short arm section 21 carrying a tongue at its lower end is pivotally supported between the ears 16 on the arm 15 by the pin 22 and maintained in adjusted positions by the thumb screw 23. A table top embodying hinged sections 24 has one of the sections secured to a plate 25 provided with depending spaced ears 26 straddling the tongue 27 and pivoted thereto by the pin 28. An arcuate arm 29 carried by the plate 25 passes through an opening 30 in the arm 21 and is engaged by a thumb screw 31 to hold the table top 24 in different angular positions.

From the above detail description it will at once be understood that various elevations and lateral adjustments for the table top may be accomplished by the adjustable connections between the arms 10 and 15 and the base support and table supporting arm 21. The angular adjustment of the table top is readily controlled by the thumb screw 31 cooperating with the curved arm 29. When it is desired to dispose the table beneath the frame of the bed, the same is moved to the dotted line position shown in Fig. 1 and so maintained by the adjusting thumb screws above described, while the clamp is slidably associated with the base support and bed rail to securely anchor the table to the frame of the bed.

While there is herein shown and described the preferred embodiment of the present invention, it is nevertheless to be understood

that minor changes may be made therein without departing from the spirit and scope thereof.

What is claimed as new is:—

- 5 A folding bed table comprising a base support having a pair of angularly disposed legs adapted to enclose the side rails of a bed, a U-shaped clamp slidably associated with one of the legs and enclosing said leg

and the adjacent side of the bed rail, a cam 10 lever carried by said clamp and adapted to engage the adjacent leg of the base support to hold the same in its clamped position, pivoted link arms carried by said base support, and a table top adjustably supported 15 by said link arms.

In testimony whereof I affix my signature.

MICHAL KOLTUNSKI.
